CLAIM

The ornamental design for a support for plant protector cones, as shown and described.

DESCRIPTION

FIG. 1 is a front elevational view of the support for plant protector cones showing our new design, in its flattened condition;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof in the position of use, the plant protector cone being shown in broken lines for illustrative purposes only.
